FIG. II

INVENTOR

John J. Roberts

UNITED STATES PATENT OFFICE

104,518

DESIGN FOR AN ELECTRIC TRAFFIC SIGNAL FOR GRADUATING TRANSIT-PERIODS

John J. Roberts, Louisville, Ky.

Application March 3, 1936, Serial No. 61,459

Term of patent 14 years

To all whom it may concern:

Be it known that I, John J. Roberts, a citizen of the United States, residing at Louisville, in the county of Jefferson and the State of Kentucky, have invented a new, original, and ornamental Design for an Electric Traffic Signal for Graduating Transit-Periods, of which the following is a specification; reference being had to the accompanying drawings, forming a part thereof.

Fig. I is a side elevational view of an electric traffic signal for graduating transit-periods, showing my new design; and Fig. II is a top plan view thereof.

The design is characterized by an oblong, rectangular body having four equal, similar sides, over which is fastened a sloping weather-protective roof and its attachment-lug; each side of said body being provided with doors; a dial-protecting hood and a clocking dial equipped with a visible timing system consisting of multiple sets of illuminative neon tubes, as shown in Fig. I.

I claim:

The ornamental design for an electric traffic signal for graduating transit-periods, as shown and described.

JOHN J. ROBERTS.
